METHOD OF DESENSITIZING CLAY-COATED RECORD SHEET

Marjorie J. Cormack and Ned A. Thacker, Dayton, Ohio, assignors to The National Cash Register Company, Dayton, Ohio, a corporation of Maryland (incorporated in 1926)

Application November 9, 1954, Serial No. 467,792

4 Claims. (Cl. 117—36)

This invention relates to a method and means for deactivating portions of a manifold copy sheet sensitized with particles of surface-active adsorbent compounds.

More particularly, the invention pertains to spot-desensitizing of manifold sheets having their receiving surfaces sensitized with particles of the class of inorganic adsorbents which act as electron acceptors in an electron donor-acceptor color-forming reaction in which the electron donor is a colorless adsorbate aromatic double bond organic compound which on adsorption on the inorganic particles is converted to a more highly polarized conjugated form, giving it a distinctive color.

Reference is made to United States Letters Patent No. 2,548,366, which issued April 10, 1951, on the application of Barrett K. Green and Robert W. Sandberg, for manifold record material sensitized with such adsorbent particles. In that patent, the receiving surface of a copy-receiving sheet is sensitized with adsorbent materials such as attapulgite, sodium aluminum zeolite material, and many others to be described. These adsorbents have the property of changing certain colorless adsorbate substances, such as 3,3 bis (p-dimethylaminophenyl) 6-dimethylamino phthalide, to a colored form when the two are in adsorption contact. The attapulgite and zeolite materials also have the ability to oxidize benzoyl leuco methylene blue and Michler's hydrol, both normally colorless, to a colored form.

In manifold systems contemplated by the mentioned patent, a top sheet has on its rear surface a rupturable film-coating containing a profusion of microscopic droplets of an oily vehicle containing the colorless adsorbate organic color reactant or reactants. The front of the second sheet is coated with a composition containing the adsorbent particles. When writing or printing pressures are applied to the front surface of the top sheet, the film on the rear surface is ruptured locally and releases the oil droplets at the pressure points, which droplets are adsorbed by the adsorbent particles on the front surface of the second sheet. This manifold system is workable with more than two sheets by having each of the middle sheets coated on the front surface with the adsorbent-containing composition, and coated on the rear surface with the rupturable oil-droplet-containing film.

As is well known, it is often desirable not to have some of the data recorded on the top sheet of a manifold pack appear on certain parts of certain of the inner sheets. By this invention, the appearance of data on any selected part of a copy-receiving sheet is prevented by desensitizing such parts of the receiving sheet by applying thereto very highly polar non-volatile organic compounds which are adsorbed by the adsorbent particles and which prevent the organic color reactant in the droplets from being adsorbed, thus preventing the color from appearing.

Such desensitizing polar compounds are preferably colorless and are used dispersed or dissolved in an oily colorless ink base vehicle, so that the desensitizing of the desired areas may be done on a printing press. Such ink base vehicles may, if desired, contain opaque sub-

stances or substances which contribute to transparency, or colored materials to match a tinted paper.

Therefore, it is an object of this invention to provide a method and means for desensitizing desired areas of receiving sheets of a manifold system in which the copy-receiving surfaces of the receiving sheets are sensitized with particles of adsorbent material that act as electron acceptors in an electron donor-acceptor color reaction, or as oxidizing agents.

10 It is another object of the invention to provide such method and means which render such desensitized areas inconspicuous.

A further object of the invention is to provide a printing fluid suitable for desensitizing such record material.

With these and incidental objects in view, the invention includes certain novel features, a preferred form or embodiment of which is hereinafter described with reference to the drawing which accompanies and forms a part of this specification.

Of the drawing:

Fig. 1 is a representation of a three-sheet manifold form with corners of the sheets turned up to allow a designation of the coatings to be made;

Fig. 2 is a representation of the top surface of the top sheet;

Fig. 3 is a representation of the top surface of the middle sheet, showing a desensitized area; and

Fig. 4 is a representation of the top surface of a bottom sheet not desensitized.

Of the many adsorbent materials which are capable of acting as electron acceptor color-reactants, the following may be mentioned:

1. Attapulgite.
2. Kaolin.
3. Pyrophyllite.
4. Sodium aluminum zeolite material.
5. Bentonite.
6. Halloysite.
7. Calcium sulfate.
8. Zinc sulfate.
9. Calcium citrate.
10. Zirconium dioxide.
11. Barium sulfate.
12. Calcium fluoride.
13. Magnesium tri-silicate.

In addition, the attapulgite, the zeolite material, kaolin, and pyrophyllite act as oxidizers for benzoyl leuco methylene blue and Michler's hydrol. The sensitization of a sheet need not be made by one of these adsorbents alone, as mixtures of them may be used.

The adsorbent or adsorbents used are applied in fine particle form to the record sheet by use of binders, as in the ordinary pigment coating of paper, except that the least possible binder is used, so as to leave exposed surfaces on the adsorbent particles for contact by the organic color-reactant material.

The adsorbent surface activity of the mentioned compounds, and many others not mentioned, may be desensitized by the following groups of non-volatile compounds:

I. Cationic quaternary ammonium salts of the following categories:

(a) Alkyl trimethyl ammonium chlorides of the general formula R—N(CH₃)₃Cl, where R is any long chain alkyl group higher than the octyl group, such as:

- (1) Dodecyl trimethyl ammonium chloride
- (2) Hexadecyl trimethyl ammonium chloride
- (3) Octadecyl trimethyl ammonium chloride
- (4) Soya trimethyl ammonium chloride

(b) Aryl trimethyl ammonium chlorides of the general

formula $R-N(CH_3)_3Cl$, where R is an aryl group, such as:

(1) Benzyl trimethyl ammonium chloride

(c) Dialkyl dimethyl ammonium chloride of the general formula $R_2N(CH_3)_2Cl$, where R is any long alkyl group higher than the octyl group, such as:

- (1) Di-coconut dimethyl ammonium chloride
- (2) Di-hydrogenated tallow dimethyl ammonium chloride
- (3) Di-lauryl dimethyl ammonium chloride

Of these quaternary ammonium salts, there also are the bromide, iodide, and acetate equivalents of the mentioned chlorides.

II. Aliphatic or aryl amine acetates, such as n-dodecyl amine acetate, in which the aliphatic or aryl groups are higher than the octyl group.

III. Amines and diamines of high molecular weight, such as:

- (1) Dodecyl amine; and
- (2) Dodecyl diamine.

IV. Substituted oxazoline, such as:

- (1) 2,4,4 trimethyl-2-oxazoline; or
- (2) 2-oleyl, 4-hydromethyl 4 methyl-2-oxazoline.

Generally, the compounds of group I are superior desensitizers, but a mixture of one of that group and one of group IV aids in the incorporation of the desensitizers in an oily printing vehicle.

Although all highly polar materials, such as water, alcohol, and other polar solvents, act as desensitizers, their effect is gone when they evaporate. It is for this reason that materials of a non-volatile nature have been specified.

The following is an example of a superior desensitizing ink containing the desensitizing compounds, in parts by weight:

Example

50 pts. oil tint base vehicle composed of a mixture of linseed oil varnish and resinous binders
25 pts. 2,4,4 trimethyl-2-oxazoline
10 pts. dodecyl trimethylammonium chloride

The oil base vehicle chosen should preferably be transparent in their films, so that the desensitizing ink will not obliterate any data previously printed in the area to be desensitized. However, if such obliteration is required, an opacifier, such as titanium dioxide, may be added. The type of oil vehicle used is chosen for the particular printing process used to apply it. Reference is made to the publication "Printing and Litho Inks," by Herbert J. Wolfe, fourth edition, published by MacNair-Dorland Company, New York city, in 1949, where in chapter III a number of oil base printing ink vehicles are specified. Another publication pertaining to printing ink vehicles is chapter #3 of the publication "Printing Inks," by Carlton Ellis, published by Reinhold Publishing Corporation, New York city, in 1940.

The desensitizing materials may be applied to the record material alone or dissolved in a volatile solvent if a printing ink vehicle is not required. The amounts of desensitizer used are not critical in any respect except that enough should be used to substantially deactivate the active and exposed surfaces of the sensitizing particles.

Among adsorbate compounds other than 3,3 bis (p-dimethylaminophenyl) 6-dimethylamino phthalide which is color-reactive with the mentioned adsorbent materials are

3,3 bis (p-diethylaminophenyl) 6-diethylamino phthalide;
3,3 bis (p-dimethylaminophenyl) phthalide;

Xanthene-9, o-benzoic acid, 3,6-bis-diethylamino-9-p-nitroanilino-lactam; and
2,4 bis [p-(dimethylaminophenylazo) anilino]-6-hydroxy sym. triazine.

Referring to the drawing, Fig. 1 represents a three-sheet statement form bound at the top 20, the first sheet being an original which contains an area 21 for the customer's name and address; and an area 22 for the cost data and selling price data, as indicated. The rear of the first, or top, sheet is coated with a rupturable gelled hydrophilic colloid film 23, containing the droplets of oily fluid containing the color-reactant. The second sheet, which is the customer's copy (Fig. 3), has on its top surface 24 the adsorbent sensitizing particles, but in the area 25 it has been desensitized by one or more of the specified desensitizing compounds. The rear surface 26 of the second sheet is coated with the oil-droplet-containing film, as film 23, on the rear of the front sheet. The front surface 27 of the bottom sheet is the same as surface 24 of the second sheet. The matter printed on the top sheet appears on each of the two undersheets except in the desensitized area 25 of the second sheet. The foregoing practical example shows the simplest method of applying the invention to a business form. The desensitization may be in differently placed areas on different undersheets if desired.

The desensitizing compounds are chosen not for any reactant effect on the organic color-reactant but only for their deactivating effect on the adsorbent. Hence they are equivalents in being highly polar, non-volatile, deactivating agents.

While the method and means of this invention have been described in connection with a number of examples of pertinent materials, it is not intended to confine the invention to such, as there are many equivalent materials.

What is claimed is:

1. The method of deactivating portions of record material sensitized with minute particles of inorganic adsorbent electron acceptor materials which cause the formation of color in an electron donor aromatic double bond color-reactant compound adsorbed thereon, by reason of an electron donor-acceptor color reaction which converts said compound to a more highly polarized conjugated form, giving it a distinctive color, including the step of applying to selected areas of the sensitized record material, before any of the organic color-reactant is applied, highly polar, non-volatile non-color-forming adsorbate material sufficient to occupy the normally available adsorbent sites on the particles of such areas.

2. The method of claim 1 in which the highly polar deactivating adsorbate is applied as a dispersion in a fluid printing vehicle.

3. The method of claim 1 in which the highly polar deactivating adsorbate used is substantially colorless.

4. The method of claim 1 in which the highly polar deactivating adsorbate is substantially colorless and is applied dispersed in a substantially colorless fluid printing vehicle.
